(57) **CLAIM**

The ornamental design for a portion of a recoil cover for an internal combustion engine, as shown and described.

DESCRIPTION

FIG. 1 is a perspective view of a portion of a recoil cover for an internal combustion engine according to [an] first embodiment of the present design;

FIG. 2 is a front elevation view of the portion of a recoil cover for [an] the internal combustion engine shown in FIG. 1;
FIG. 3 is a top plan view of the portion of a recoil cover for [an] the internal combustion engine shown in FIG. 1;
FIG. 4 is a bottom plan view of the portion of a recoil cover for [an] the internal combustion engine shown in FIG. 1;
FIG. 5 is a right side elevation view of the portion of a recoil cover for [an] the internal combustion engine shown in FIG. 1; [and]
FIG. 6 is a left side elevation view of the portion of a recoil cover for [an] the internal combustion engine shown in FIG. 1[1];

FIG. 7 is a perspective view of a portion of a recoil cover for an internal combustion engine according to a second embodiment of the present design;

FIG. 8 is a front elevation view of the portion of a recoil cover for the internal combustion engine shown in FIG. 7;

FIG. 9 is a top plan view of the portion of a recoil cover for the internal combustion engine shown in FIG. 7;

FIG. 10 is a bottom plan view of the portion of a recoil cover for the internal combustion engine shown in FIG. 7;

FIG. 11 is a right side elevation view of the portion of a recoil cover for the internal combustion engine shown in FIG. 7;

FIG. 12 is a left side elevation view of the portion of a recoil cover for the internal combustion engine shown in FIG. 7;

FIG. 13 is a perspective view of a portion of a recoil cover for an internal combustion engine according to a third embodiment of the present design;

FIG. 14 is a front elevation view of the portion of a recoil cover for the internal combustion engine shown in FIG. 13;

FIG. 15 is a top plan view of the portion of a recoil cover for the internal combustion engine shown in FIG. 13;

FIG. 16 is a bottom plan view of the portion of a recoil cover for the internal combustion engine shown in FIG. 13;

FIG. 17 is a right side elevation view of the portion of a recoil cover for the internal combustion engine shown in FIG. 13;

FIG. 18 is a left side elevation view of the portion of a recoil cover for the internal combustion engine shown in FIG. 13.

The broken lines shown in FIGS. 1-[6] 18 are for illustrative purposes only and form no part of the claimed design.

1 Claim, 12 Drawing Sheets

Matter enclosed in heavy brackets [ ] appears in the original patent but forms no part of this reissue; matter printed in italics indicates the additions made by reissue.
